GUN TURRET

Irwin Chase and Burns Darsie, Bayonne, N. J.,
assignors to Electric Boat Company, Groton,
Conn., a corporation of New Jersey

Application November 20, 1942, Serial No. 466,260

14 Claims. (Cl. 89—37)

1
Our invention relates to ordnance, and contemplates a new turret mounting guns particularly for anti-aircraft fire from small naval craft.

The broad object of our invention is to provide a self-contained protected unit for a battery of guns, for a single gunner, and to enable him to aim his guns rapidly and to control their fire with ease. In the accomplishment of that object, we fixedly mount appropriate guns and their operating mechanism on a platform in the form of an armored cab or cradle, which the gunner is to occupy, said cab or cradle being hung from horizontal trunnions in bearings supported on a turn-table rotatable on a vertical axis upon a base bolted to the deck; thus, the gunner at all times maintains a relatively fixed position relative to his guns, and the platform has universal movement whereby he can get on and follow the target.

Within that broad object, our invention has numerous specific objects, which will be made point of as this description proceeds, and which are accomplished, as will be seen. Among these are the inherent steadyng of gun recoil, special protection for the more vital regions in the turret, safety features which permit continued operation notwithstanding damage to some of the parts, simplicity of construction and operation and sensitiveness of control, and selective firing.

Although, as stated, the turret of our invention is particularly conceived for use on small naval craft, it is of course adaptable to larger vessels, and, as will appear, it may also be useful on military land vehicles or as a stationary outfit.

The turret of our invention is illustrated in the accompanying drawings in which—

Figure 1 is a side elevational view, part of the housing being shown in section in order to reveal part of the means for mounting the turn-table;

Figure 2 is a front elevational view, parts being broken away and shown in section to reveal the means for operating the turntable and for mounting the cab;

Figure 3 is a plan view, part being broken away to show a horizontal section at a lower level;

Figure 4 is a front elevational view, with the front of the cab removed in order to reveal the arrangement of the equipment within it;

Figure 5 is a longitudinal vertical sectional

2
view taken on the plane of the line 5—5 of Figure 4 and looking in the direction indicated by the arrows;

Figure 6 is a view similar to Figure 4, except that it is schematic in part in order to show the arrangement of certain of the parts and mechanisms within the cab;

Figure 7 is a view similar to Figure 1, without showing details, but illustrating the action of 10 the cab about its horizontal axis;

Figure 8 is a diagrammatic view of the hydraulic system for operating the cab in train and in elevation;

Figure 9 is the electrical wiring diagram; and 15 Figure 10, 10A and 10B are diagrammatic views of the hydraulic system for firing the guns.

The same reference characters are applied to the same parts throughout the various figures.

Referring first to Figures 1, 2 and 5:
20 The entire structure is mounted on a single stationary base 11, which is circular about the vertical axis indicated by the vertical dot-and-dash lines in Figures 1, 2 and 5, and which is a casting of substantial size and weight and is suitably bolted to the deck.

25 A turn-table is mounted on this base, and this turn-table comprises a main supporting ring 12, carrying the circular crowned covering apron 13 of iron sheet, this apron being formed with a transverse tunnel housing 14, forming the bight of a yoke to which further reference will be made presently. A downwardly extending flange 15 carries the housing band 15a about the periphery of this apron.

30 The ring 12 is provided with a plurality of short inwardly extending arms 16, each of which is provided with a bearing 17, in which is mounted a stub shaft 18 carrying a roller 19, and these rollers run upon the circular track 20 formed on the base 11. Extending centrally downward, from the inside of the apron 13, is a tube 21, which centers the turn-table on the base, with the rollers 19 on the track 20, by engagement in the central bearing 22 on the base, the lower end of the tube being provided with a hold-down nut 23 by means of which the turn-table and base are held together, with adequate play for free rotation of the one upon the other.

35 Concentric with and inwardly of the track 20, an upwardly extending rib 24 is provided on the

base 11, and a ring gear 25 is fixed upon that rib. Within the tunnel housing 14, two hydraulic motors 26 are mounted, each with its shaft vertical, on the supporting plates 27 fixed to the ring 12, and the shaft of each motor is provided, at its lower end, with a pinion 28 meshing with the ring gear 25. Although but one such hydraulic motor may be used, there are preferably two such motors, with pinions engaging the ring gear, one on each side of the turn-table.

The yoke, which has already been referred to, comprises the tunnel housing 14 and the hollow iron sheet uprights 29, 29; and the gun platform, in the form of a cab or cradle, is hung in this yoke on the horizontal axis indicated by the horizontal dot-and-dash line in Figure 2.

This cab is formed of armor plate, comprising the bottom 39, which curves into the back wall 31, side walls 32 and 33, and front wall 34, which, at its upper part, curves upwardly and backwardly to the top plate 35, hinged at 36. The cab is hung on its horizontal axis by way of tubular trunnions 37, 37, secured to the side walls 32 and 33 over alined openings therein, these trunnions being mounted in bearings 38 in the upper ends of the uprights 29, as shown particularly in Figure 2.

Reference is now made to Figure 1, wherein is illustrated the means for swinging the cab on its horizontal axis. This elevating device is in the form of a hydraulic ram, comprising a cylinder 41 and piston 42, the former being pivotally connected at 47 by means of a stem 46 to a lug 48 formed on the adjacent upright 29 of the yoke near the bottom thereof. The piston 42 has its connecting rod 43 pivotally engaged at 44 in a socket plate 45 secured in the side wall 33 of the cab. The cylinder has connected thereto flexible hydraulic conduits, leading from within the cab, as will be described more fully later in this specification. A cylinder and plunger arrangement such as this is provided also on the other side of the cab, as indicated in Figure 3.

The hydraulic systems will be later described. For the present, let it be understood that when the hydraulic motors 26 are operated, the pinions on their shafts, engaging the fixed ring gear 25, will effect rotation of the turn-table, and with it the yoke and cab, about the vertical axis, and that the supplying of fluid under pressure to one end or the other of the cylinder 41 swings the cab in the yoke about the horizontal axis, the latter action being illustrated in Figure 7.

A plurality of guns are mounted in the cab, fixedly and with their barrels parallel, and extending forwardly through the front wall 34 and top plate 35. Some of the guns are mounted on the side walls of the cab, as will be seen; others on the cab frame-work 49, 50. They are automatic guns, of appropriate caliber, and there are shown six smaller caliber guns and two of larger caliber, arranged relatively to each other as best illustrated in Figure 2, where it will be seen that the larger caliber guns are at the middle of the cab with the smaller caliber guns variously grouped about them. This arrangement of the guns is dictated by the desire to have the heavier guns, with the heavier recoil, near the center of the structure, by the nature of the guns and their attendant mechanisms, and by provision for the gunner's position.

The gun construction, per se, is not part of this invention, and for simplicity, there is just sufficient showing of them to indicate their nature, to illustrate their mounting, and to repre-

sent those parts thereof that are directly concerned with their incorporation in the turret and in the firing system.

The smaller caliber guns are shown at 51, 51, two of them being located at the sides, and higher than the other four, being supported from the side walls 32 and 33, respectively, by means of brackets 52, 52; the other four are mounted in a row upon brackets 53, 53 on the frame-work 49, 50.

The ammunition for these smaller caliber guns is in the form of cartridges held together in the form of a belt by clips, the belt of cartridges being fed to the chamber of the gun at one side thereof, the clips being ejected at the other side, and the shells being ejected at the bottom. As best shown in Figure 4, the two side guns of this small caliber group are fed, by way of a chute 54, from a magazine box 55 in a magazine compartment below. The clip ejector chute 56, on the other side of the gun leads through an opening in the side wall 32 or 33 to the outside, and the shell ejector chute 57 leads from the bottom of the gun through another opening in the side wall 32 or 33 to the outside.

Each of the other four smaller caliber guns is fed from a magazine box 55 below by means of a chute 58, but in these cases the clip and shell ejector chutes are differently formed, as indicated respectively at 59 and 60. Utilizing the fact that there are both right and left feed and ejector arrangements, the ejector chutes for the two right hand guns and those for the two left hand guns are respectively merged into a common ejector chute 61 leading downwardly and rearwardly through the bottom of the cab to the outside.

Access to the magazine compartment is had by two doors 62, 62, hinged at 63, 63 and clasped at 64, through which empty magazine boxes may be removed and charged ones substituted.

This magazine compartment is specially protected by the secondary oblique armor plates 65, 65, welded in the positions shown in Figure 3. By this arrangement it is impossible to register a square hit on both outer and inner skins.

The larger caliber guns 66, 66 are fixedly mounted on the cab frame-work by means of the support bar and bracket 67 and 68. These guns are fed from magazines 69, 69 which are brought to and attached to the guns in a known manner, the shells being ejected from the guns at the bottom thereof and being carried away by means of the chutes 70, 70, leading downwardly and rearwardly through the back of the cab to the outside.

It will be observed that these larger caliber guns are considerably longer than the smaller caliber guns, extending substantially from the back wall of the cab forwardly through and considerably beyond the front wall. The smaller caliber guns, on the other hand, are considerably shorter, extending only about half way back from the front wall, leaving room behind those on one side for the gunner. A seat 71, with a back and head rest 72, 73 is provided for him in one of these open corners, and he occupies this seat in a relatively fixed position at all times during the aiming and firing of his guns.

In front of him, and between his knees when 70 in seated position, is a directional control handle 74, which handle has movement forward and back, and from side to side, for purposes now to be described. The position of this handle will be seen from Figures 3, 5 and 6. In its movement from side to side, and through a connect-

ing rod 75, it operates a control valve 76, this valve being a three-position valve enabling a flow of operating fluid in one direction, or the reverse direction, or no flow at all. By the use of this valve, the gun platform is trained, i. e. it controls the movement of the cab about the vertical axis. It is only movement of the control handle 74 from side to side that is transmitted to the valve 76, back and forth movement thereof having no effect on that valve. Back and forth movement of the control handle, without effect on the valve 76, is transmitted to another valve, 77, which is similar to the valve 76 in that it also has three positions, one for flow of operating fluid in one direction, one for flow in the reverse direction, and one for no flow at all; by this means the gun platform is operated in elevation, i. e. the cab is swung about its horizontal axis.

Sighting means is provided as follows: On the side wall 32, at the left of the gunner, there is secured a plate 78 which, by way of a hinge 79, mounts a bracket 80 carrying a sight 81, preferably a unit sight, having a sighting leveller 82 carrying an eye socket 83. The sighting device is swung on its hinge 79, out of the way, in order to enable the gunner to get into his position, after which it is swung down before him into position for use. In position on the seat, the gunner, with his sight before him, and with the control handle 74 between his knees, as will be seen, is enabled to impart universal movement to the cab, training it by moving the control handle from neutral to one side or the other, and elevating it by moving the control handle from neutral backward or forward.

The operating system, thus governed by this control handle, will now be described.

An electric motor 84 is mounted on the back wall of the cab, and another similar motor 85 is conveniently mounted somewhat lower and at the side opposite the gunner, and these motors, connected in parallel, are supplied with current in the following manner:

As already stated, it is a feature of our turret that it is structurally entirely self-contained; all it requires from outside source is a supply of electric current and this is done by cable leads from any suitable source to the slip rings 86, 87 fixedly mounted on the disc 88, of insulating material, mounted on the stationary base 11, under the apron 13 and tunnel housing 14, and engaged by the brushes 89, 89, as shown in Figure 5.

Referring now to the electrical wiring diagram, Figure 9, it will be seen that one of these brushes 89 is grounded to the turret structure, and the other is connected, by means of conductor 90, with one terminal of the relay switch 91. This relay switch is in the cab and the conductors from the brushes are run through the terminal housing 14 and one of the uprights 29. The other terminal of that switch leads, by way of conductor 92, to the terminal bus 93, which is connected, by way of conductor 94, to one terminal of the electric motor 84, and by way of conductor 95 with one terminal of the electric motor 85, the other terminals of the motors being grounded, as indicated. The relay switch 91 is of known type, in which an operating coil is normally connected, in effect, across the leads 90 and 92 in series with the operating switch 96, to actuate a switch blade into and out of bridging relation to the conductors 90 and 92. The operating switch 96 is conveniently placed on the end of the control lever 74 and is preferably made a "dead

man's" control, i. e. a normally open push button which is closed against spring pressure and which automatically opens the circuit when pressure on the button is released. If desired, storage batteries may be disposed in the cab for emergency use in the event of failure of the outside source of current, and they may, if desired, be placed toward the rear in order to provide additional counterweight for the gun barrels.

Each of the motors 84 and 85 operates two hydraulic pumps, one at each end of its shaft, these pumps being marked 97, 98, 99 and 100. These are the pumps which supply the pressures to operate the hydraulic motors 26, 26 and the hydraulic rams 41, 41. The operating fluid is preferably oil.

The hydraulic system embodying these driving and driven elements, and their controls, will now be described by reference to Figure 8. Referring first to the means for training the turret:

The hydraulic motors 26, 26 are connected in parallel, the left hand connection of each being connected, by means of conduit 101, with the transverse control valve 76, to which the high pressure outlets of the pumps 97 and 99 are connected by means of conduits 102, 102. The conduits from the hydraulic motors are passed through the tunnel housing 14, through the uprights 29, and through the tubular trunnions 30 into the cab. Each of the conduits 102 has in it a check valve 103 and, where they come together, they enter a pressure relief valve 104 leading to the control valve 76. Excess fluid released by the pressure relief valve 104 is conveyed by conduit 105 to return conduit 106 leading back to the reservoir 107, which tank is connected with the low pressure inlets of the pumps 97 and 99 by way of the conduits 108 and 109, respectively. The reservoir 107 is shown in detail in Figure 6. It has in it a piston 107a, loaded by a spring 107b, and a check valve 107c is provided in the piston. Oil filled at the upper side of the piston is charged into the system, past the check valve, by raising the piston by means of the handle 107d. The three connections to the reservoir are below the piston, and the effect is to maintain a small pressure on the low pressure side of the system. The piston and check valve are fit to a slight leakage, permitting rapid passage of air but only very slow leakage of oil. The purpose is to keep out of the system air which would tend to cause the oil to foam. The control valve 76 is connected with the return conduit 106 by means of conduits 110 and 111, and conduit 112 connects it with both of the right hand connections of the hydraulic motors 26, 26.

As already stated, the control valve 76 is a three-way valve, enabling (a) the pressure coming in by way of the conduits 102 to be applied to the conduit 101, the return flow being by way of the conduits 112, 110 or 111, and 106, to operate the hydraulic motors 26, 26 in one direction, (b) that pressure to be applied to the conduit 112, the return flow being by way of the conduits 101, 110 or 111, and 106, to operate these motors in the opposite direction, or (c) to bypass the pressure coming in by way of the conduits 102 directly through the conduits 110 and 111 to the return conduit 106.

When the gunner, in his position, moves the control handle 74 to the left, condition (a) prevails to operate the hydraulic motors and their pinions in that direction to train the cab counterclockwise. When he moves the control handle

to the right, reverse action takes place to train the cab in clockwise direction. When the control handle is in mid-position, athwartships, it is in neutral, i. e. (c) position, the hydraulic motors are at rest, and there is no training of the cab. In this way, the gunner is enabled easily to train his cab, either rapidly by wide open movement of the transverse valve or slowly by slight movement of it, to get his battery of guns quickly in the vertical plane of his target and to follow as slowly as its speed may require. It will be observed that there are two pumps and two motors, each pair in parallel, so that, if either pump or either motor is disabled, there will still be one motor and one pump in effective action. While such disabling will reduce the speed of operation to one-half, there can still be operation.

Still referring particularly to Figure 8, we shall now describe the means for elevating the cab and for controlling such operation.

The other two hydraulic pumps 98 and 100, on the motors 84 and 85, respectively, have their high pressure outlets connected to the control valve 77 by way of conduits 113 and 114, respectively, each of these conduits having in it a check valve 115, these conduits uniting at a pressure relief valve 116 which has its normal outlet directly connected with the control valve 77 and its excess outlet connected with the return conduit 106 which, as already stated, leads back to the main hydraulic supply tank 107. The control valve 77, which, as already indicated, is of a character similar to that of the control valve 76, governs the operation of the hydraulic rams in manner as follows: The upper end of each cylinder 41 is connected with the valve 77 by means of the conduit 117, and the lower end thereof is connected with the valve by means of the conduit 118, these conduits being flexible and passing from the rams into the uprights 29 and through the trunnions 37. The low pressure outlets from valve 77, by way of the conduits 119 and 120, are connected with the return passage 106 leading back to the supply tank 107. The valve 77 is such that the pressure coming from the pumps 98 and 100, by way of the conduits 113 and 114, respectively, may be applied to either of the outlets 117 or 118, either to move the plunger inwardly in the cylinder, or outwardly, respectively; and, in either case, the fluid return is by way of the other and the conduits 119 or 120 and 106. When the control handle 74, which operates the valve 77, is moved rearwardly, pressure is applied to move the pistons 42 inward in their cylinders 41, thus to swing the cab backwardly about the horizontal axis, ultimately to the position shown in dotted lines in Figure 7; when the control handle is moved forwardly, pressure is applied to move the pistons outwardly, and the cab swings down toward and to its normal position shown in Figure 1. The relief valve 116 serves to prevent the building up of excess pressure at the limits of movement of the pistons in their cylinders. When the control handle is in mid-position, fore-and-aft, the incoming high pressure is by-passed to the return conduits 119, 120 and 106, i. e. it is in neutral and there is no operation of the cab in elevation. Here again, it will be observed that there are two rams and two motors, each pair in parallel, so that, if either ram or either motor is disabled, there will still be one ram and one motor in effective action.

Thus, as the gunner sits in his position rela-

tively fixed to his sight and his guns, he may quickly bring his guns upon his target, both in train and in elevation, thereafter keeping on his target by careful manipulation of the control handle 74, always with his finger down on the button of the switch 96 in order to keep the turret in operation.

We shall now describe the means for firing the guns. As before stated, they are all automatics, i. e. they continue to fire shots in rapid succession so long as the trigger is held down and cartridges are fed, and they are fired in bursts as occasion may require. Devices for applying pressure to the trigger hydraulically are known, and they have therefore been indicated merely diagrammatically at 121 for the small caliber guns and at 122 for the large caliber guns. These actuators comprise essentially a cylinder and piston and are operated simply by the application of hydraulic pressure, and the manner in which that is done in the present instance will now be described, reference being had to Figures 3, 5, 6, 10, 10A and 10B.

The means for this purpose is a static hydraulic system, governed by foot pressure, with selective control in respect of choice of guns and in order of firing if desired.

A master cylinder 123 is provided, the piston in that cylinder being operated by an appropriately placed treadle 124 through suitable linkages 125. This master cylinder, on the pressure side of the piston, is connected, by way of conduit 126, with the hydraulic operating mechanisms of the guns through three-port two-position control valves on a selector panel 127, mounted on the side wall 32 of the cab at the left of the gunner. Accordingly, in the arrangement herein shown, this selector panel comprises six such valves 128 for the small caliber guns and two such valves 129 for the large caliber guns. The high pressure ports of these valves are all connected with the conduit 126. The second port of each of these valves is connected with the actuator of a particular gun, these conduits being indicated at 130, 130. The third port of each of these valves is connected with the low pressure end of the master cylinder by means of conduit 131. Each of these valves has an operating finger piece 132 and it may thereby be set either directly to connect the high pressure end of the master cylinder with the gun actuator, with the release outlet closed, which is the firing position, as shown in Figure 10A, or to connect the gun actuator directly with the low pressure side of the master cylinder, with the high pressure inlet of the valve closed, which is the safe position, as shown in Figure 10B.

When the gunner depresses the treadle 124, pressure is exerted upon the actuator of whichever guns have been selected for operation by the turning of valves on the selector panel, and in this wise any combination of guns can be fired. Also, the pressures at which the various triggers operate may be so fixed by spring adjustment that, as the operator depresses the treadle 124 he will bring the selected guns successively into action, for instance beginning with the two outside small caliber guns and ending with the two large caliber guns. The cab and all that it contains, hung from the trunnions, itself constitutes the necessary mass to steady the gun recoil.

In the foregoing, we have described the particular turret which we have actually built and operated, attaining the objects of our invention,

and it will be understood that numerous modifications might be made without departing from the spirit and scope of our invention, particularly in its broader aspects. The appended claims are drawn accordingly.

We claim:

1. A turret comprising upright hollow supporting members, an armored gun cab hung from trunnions on a horizontal axis in said upright supporting members, a hydraulic ram pivoted at one end to said gun cab at a distance from said axis and at its other end to one of said upright supporting members, a pump in said cab, a conduit connecting said pump and said ram passing through one of said supporting members and its associated trunnion, a valve in said conduit, an electric motor in said cab operating said pump, and conductors for said motor passing through one of said supporting members and the associated trunnion.

2. A turret comprising upright supporting members, a gun platform hung on a horizontal axis on said upright supporting members, a pair of hydraulic rams each pivoted at one end to one side of said gun platform, and at its other end to the adjacent upright supporting member, said rams being hydraulically connected in parallel, a pair of hydraulic pumps connected in parallel on said platform, and conduits connecting said pumps and said rams for supplying to the latter liquid under pressure.

3. A turret comprising a base, a circular track on said base, a ring gear fixed on said base, a turn-table rotatable on said track, a pair of hydraulic motors connected in parallel fixed on said turn-table, each having a pinion meshing with said ring gear for rotating said turn-table, a gun platform hung on a horizontal axis on supporting uprights on said turn-table, a pair of hydraulic rams each pivoted at one end to one side of said gun platform and at its other end to the adjacent upright, said rams being hydraulically connected in parallel, a pair of electric motors on said gun platform, each electric motor having two pumps on its shaft, conduits connecting one pump of each electric motor in parallel with one pump of the other electric motor and with said hydraulic motors for supplying thereto liquid under pressure, a supply tank on said platform connected to said pumps, conduits connecting the other pumps of said electric motors in parallel and with said rams for supplying thereto liquid under pressure, and return conduits leading to said tank for returning thereto liquid from said hydraulic motors and from said rams.

4. A turret comprising a cab with a bottom and front, back and side walls, said cab being hung to swing on a horizontal axis, guns mounted in fixed position to said cab and extending through the front wall thereof, a gunner's seat at the back and side of said cab, and sighting means hingedly mounted on the adjacent side wall of said cab in front of said gunner's seat movable upward into a position clear of said seat and downward into a position overlying said seat.

5. A turret comprising a box-like armored cab substantially rectangular in plan mounted for rotation about a vertical axis and about a horizontal axis with its major portion below the latter axis, a plurality of guns mounted in fixed positions in the upper portion of said cab extending forwardly therefrom, certain of said guns being of relatively small caliber with their breech ends spaced a considerable distance from

the back of said cab and certain others of said guns being of relatively large caliber with their breech ends in proximity to the back of said cab, said large caliber guns being disposed remote from the sides of said cab and certain of

5 said small caliber guns being disposed adjacent the sides of the cab, a gunner's seat in the lower rear portion of said cab adjacent one side thereof in back of certain of said small caliber guns, power means for turning said cab in either direction about either of said axes selectively for moving it and with it said guns in traverse and in elevation, and means within said cab in front of said seat for controlling said power means.

15 6. A turret comprising a box-like armored cab substantially rectangular in plan mounted for rotation about a vertical axis and about a horizontal axis with its major portion below the latter axis, a plurality of guns mounted in fixed positions in the upper portion of said cab extending forwardly therefrom, certain of said guns being of relatively small caliber with their breech ends spaced a considerable distance from the back of said cab and certain others of said guns

20 25 being of relatively large caliber with their breech ends in proximity to the back of said cab, said large caliber guns being disposed remote from the sides of said cab and certain of said small caliber guns being disposed adjacent the sides

30 35 of the cab, a gunner's seat in the lower rear portion of said cab adjacent one side thereof in back of certain of said small caliber guns, power means for turning said cab in either direction about either of said axes selectively for moving it and with it said guns in traverse and in elevation, said power means comprising primary power units within said cab adjacent the other side thereof in back of certain other of said small caliber guns, and means within said cab in front

40 of said seat for controlling said power means.

7. A turret comprising a box-like armored cab substantially rectangular in plan mounted for rotation about a vertical axis and about a horizontal axis with its major portion below the latter axis, a plurality of guns mounted in fixed positions in the upper portion of said cab extending forwardly therefrom, certain of said guns being of relatively small caliber and certain other of said guns being of relatively large caliber, said

45 small caliber guns being spaced apart transversely of said cab with certain thereof adjacent the sides of the cab, said large caliber guns being disposed remote from the sides of the cab and generally at the transverse midportion

50 55 thereof, and power means for turning said cab in either direction about either of said axes selectively for moving it and with it said guns in traverse and in elevation.

8. A turret comprising a box-like armored cab substantially rectangular in plan mounted for rotation about a vertical axis and about a horizontal axis with its major portion below the latter axis, a plurality of guns mounted in fixed positions in the upper portion of said cab extending forwardly therefrom, certain of said guns being of relatively small caliber and certain other of said guns being of relatively large caliber, said

60 65 small caliber guns being spaced apart transversely of said cab with certain thereof above and certain others thereof below said horizontal axis and said large caliber guns being disposed substantially in the plane of said horizontal axis

70 75 taken transversely of said cab, and power means for turning said cab in either direction about either of said axes selectively for moving it and

with it said guns in traverse and in elevation.

9. A turret comprising a box-like armored cab substantially rectangular in plan mounted for rotation about a vertical axis and about a horizontal axis with its major portion below the latter axis, a plurality of guns mounted in fixed positions in the upper portion of said cab extending forwardly therefrom, certain of said guns being of relatively small caliber and certain other of said guns being of relatively large caliber, said small caliber guns being spaced apart transversely of said cab with certain thereof above and certain others thereof below said horizontal axis and said large caliber guns being disposed substantially at the transverse midportion of said cab in the plane of said horizontal axis taken transversely of said cab, and power means for turning said cab in either direction about either of said axes selectively for moving it and with it said guns in traverse and in elevation.

10. A turret comprising upright supporting members one of which is hollow, an armored cab hung on said members for turning movement about a horizontal axis, a hydraulic ram attached to said cab and to one of said uprights for turning said cab about said axis, a hydraulic pump in said cab, conduit means connecting said pump to said ram passing from said cab into said hollow upright member and thence to said ram, and valve means in said cab controlling communication between said conduit means and said pump.

11. A turret comprising upright supporting members one of which is hollow, an armored cab hung on said members for turning movement about a horizontal axis, a hydraulic ram attached to said cab and to one of said uprights for turning said cab about said axis, a hydraulic pump in said cab, conduit means connecting said pump to said ram passing from said cab into said hollow upright member and thence to said ram, a gunner's seat in said cab, valve means in said cab controlling communication between said conduit means and said pump, and a control handle in front of said seat for operating said valve means.

12. A turret comprising a covered armored turntable rotatable about a vertical axis, hollow upright supporting members on said turntable, an armored cab substantially rectangular in plan hung between said upright members for turning movement about a horizontal axis by hollow trunnions opening into said members and into said cab, hydraulic rams adjacent said upright members attached to said turntable and to said cab for turning the latter about said horizontal axis, power driven pumps in said cab, conduits passing from said pumps through said trunnions and upright members to said rams for supplying thereto liquid under pressure, return conduits passing from said rams through said upright members and trunnions to the interior of said cab for discharging liquid from said rams, means comprising hydraulic motors underlying said turntable for rotating the latter, conduits passing from said pumps through said trunnions and upright members to said motors for supplying thereto hydraulic liquid under pressure, return conduits passing from said motors through said uprights and trunnions to the interior of said cab for discharging liquid from said motors, and means in said cab controlling flow of liquid through said conduits to and from said rams and motors.

13. A turret comprising a covered armored turntable rotatable about a vertical axis, hollow

upright supporting members on said turntable, an armored cab substantially rectangular in plan hung between said upright members for turning movement about a horizontal axis by hollow trunnions opening into said members and into said cab, hydraulic rams adjacent said upright members attached to said turntable and to said cab for turning the latter about said horizontal axis, power driven pumps in said cab, conduits connecting said pumps and reservoir to said rams for supply thereto of liquid under pressure and discharge of liquid therefrom, said conduits passing through said upright members and said trunnions, means comprising hydraulic motors underlying said turntable for rotating the latter, conduits connecting said pumps and reservoir to said motors for supply thereto of liquid under pressure and discharge of liquid therefrom, said second mentioned conduits passing through said upright members and trunnions, and means in said cab controlling flow of liquid through said conduits to and from said rams and motors.

14. A turret comprising a turntable rotatable about a vertical axis having an armored covering and a substantially transversely extending armored tunnel housing, hollow upright supporting members carried by and opening at their lower ends into said housing, an armored cab substantially rectangular in plan hung between said upright members for turning movement about a horizontal axis by hollow trunnions opening into said members and into said cab, hydraulic rams adjacent said upright members attached to said turntable and to said cab for turning the latter about said horizontal axis, electric motors in said cab, slip rings underlying said tunnel housing, leads to said slip rings from an external source of electric current passing through said tunnel housing, leads passing from said slip rings through said upright members and trunnions to said motors, pumps in said cab driven by said motors, a hydraulic liquid reservoir in said cab, conduits connecting said pumps and reservoir to said rams for supply thereto of liquid under pressure and discharge of liquid therefrom, said conduits passing through said upright members and said trunnions, means comprising hydraulic motors underlying said tunnel housing for rotating said turntable, conduits connecting said pumps and reservoir to said motors for supply thereto of liquid under pressure and discharge of liquid therefrom, said second mentioned conduits passing through said upright members and trunnions, and means in said cab controlling flow of liquid through said conduits to and from said rams and motors.
